[57] CLAIM

The ornamental design for a combined foot valve and strainer, as shown and described.

DESCRIPTION

FIG. 1 is a side elevational view of a combined foot valve and strainer showing my new design, the other side views being the same as the side view shown; FIG. 2 is an elevational view of one end thereof; and FIG. 3 is an elevational view of the opposite end thereof from that shown in FIG. 2.

The foot valve and strainer is attached to the end of a suction hose and disposed in a liquid to be drawn up into the hose.
